UNITED STATES PATENT OFFICE.

JOHN KOWOLCHUK, OF NEW YORK, N. Y.

SAFETY SHELL.

Application filed March 1, 1927. Serial No. 171,869.

This invention relates to safety shells and in particular to a device adapted to be incorporated therein to prevent premature explosion.

5 A particular object of the invention is to provide in connection with an explosive shell, a safety device which may be embodied in the head thereof and which can be used during the loading and handling of the shell 10 to prevent ignition of the explosive charge.

15 A further object of the invention is to provide a simplified mechanism which may be operated to set the explosive cap in position when the shell is about to be placed flush but which, during transportation may be used to prevent accidental explosion of the shell.

20 A still further object of the invention is to provide a simplified mechanism which may be made up at small cost and which can be incorporated in the shell construction, be positive in its action and which will make the handling of shells of a high explosive 25 nature, quite safe.

25 To enable others skilled in the art to fully comprehend the underlying features of my invention that they may embody the same in the various modifications in structure and relation contemplated, a drawing depicting 30 a preferred form has been annexed as a part of this disclosure and in such drawing, similar reference characters denote corresponding parts throughout all the views, of which

Figure 1 is a view in perspective of an explosive shell showing my safety latch setting key.

Figure 2 is a view in perspective of the safety latch setting key as it would appear when removed from head of the shell.

40 Figure 3 is a view in sectional elevation, the same being taken longitudinally of the explosive shell having incorporated therein, my improved safety device.

45 Figure 4 is a sectional view taken on the line 4-4 of Figure 5 and shows the position of the cap bar when the explosive cap is in position.

Figure 5 is a view of the end of the shell in section showing the position of the safety

mechanism after the setting key has been 50 detached from the shell head, and

Figure 6 is an enlarged fragmentary view 55 in sectional elevation of the cap bar showing the incorporation therein of a safety rubber pad and also of the explosive cap.

Referring to the drawings in detail, 5 indicates the body of an explosive shell of the type commonly used and which is held at one end in the shell case 6 and is provided 60 at its forward end with the head 7 surrounded by the crown 8. The crown 8 is threaded to the head 7 which, in turn, has threaded connection with the body 5, the body 5 being provided with an end closure 9 and so frictionally held in the open 65 end of the shell case 6, the shell adjacent the end of the shell case being provided with the usual rifling band 10, the body of the shell is provided with the explosive charge 11, as is common in such type of shell, which 70 charge is ignited through the medium of a detonator of gun cotton or the like 12, which is positioned in a bore 13 formed in the front end wall 14 of the shell body. This wall 14 adjacent the bore 13 is provided with an 75 extended portion 15 which forms a base across which the cap bar 16 slides, the cap bar being slidably mounted in a suitable standard 17 secured through the medium of the screw 18 to the inner wall of the head 7 and being so disposed that, at its outer end, 80 it allows sliding movement therethrough of said cap bar 16. This cap bar in its free end 19 is engaged by the free end of a spring 20, to which, at its mid portion, the plunger 21 85 is secured, the spring being secured to the crown of the shell in any suitable manner such as by the screw 22. The head of the shell is provided with an undercut slot 23 and an opening 24 connecting the slot with 90 the interior of the head, the slot being arranged to accommodate the flat end 25 of the safety latch setting key 26. The key extends longitudinally of the shell head and crown and terminates in a spring clip end 95 27 which is adapted to fit the shank 29 of the firing pin 28, the end thereof beyond the end 27 being provided with an enlarged head

portion 30 which is held in spaced relation with the crown by the clip 27. The setting key 26 is provided in its mid portion with the finger piece 31 whereby the same can 5 be detached from the shell to set the mechanism in position to cause the discharge thereof.

It will be evident therefore that in shells 10 of the kind which explode when they strike the ground, it is necessary that the firing pin be maintained in advance position so that when the same strikes the ground it will set off the explosive cap to ignite the gun cotton which will, in turn, ignite the 15 explosive charge and it is evident that the setting key 26 will prevent depression of the firing pin due to the fact that the clip 27 on the end thereof engages beneath the head 30 of the firing pin and prevents its 20 movement toward the crown of the shell. In order to doubly ensure against explosion, I have provided in the cap bar 16, a pad of rubber or other like material 32 which will prevent the firing pin from igniting 25 the gun cotton charge. This rubber pad may be incorporated in the cap bar in any suitable manner and spaced longitudinally therefrom. I provide the explosive cap 33 which may be positioned beneath the firing 30 pin automatically by the withdrawal of the setting key, which will be hereinafter explained.

This cap bar 16 has sliding movement 35 through the bifurcated end 34 of a firing pin sleeve 35, the sleeve being suitably secured in the crown 8 and being provided with a central wall 36 against which abuts a spring 37, the spring surrounding the firing pin 28, normally urging the same in an outward 40 direction through the medium of its contact with a pin 38 fixed in the firing pin 28 at one end of the spring 37, it of course being understood that the spring at its opposite end, bears against the wall 36 of the sleeve 45 35 and thus normally urges the firing pin outwardly. The pin is retained in the position shown in Figure 3 or in its safety position through the medium of a lug 39 formed thereon and arranged to contact with the 50 latch or slide 21 and it will be evident that when the latch 21 is maintained in the position shown in Figure 3 by reason of the spring 20, the firing pin will be prevented from having an outward movement. However, 55 when the safety latching key 26 is withdrawn so that its clip end 27 disengages the firing pin and its opposite end is drawn out of the slot 23, the cap bar 16 will be immediately released by reason of the fact 60 that the reduced end of the setting key 26 which passes through an opening 40 in the cap bar 16 has been removed thereby allowing the spring 20 to draw the cap bar transversely through the bifurcated end 34 of the

sleeve 35 to remove the pad 32 from alignment with the firing pin 28 and position thereunder the detonating cap, 33, it being evident that the detonating cap will then be resting upon the projection 15 of the wall 14 of the shell body and will be directly under the firing pin so that when the same is projected thereagainst, the cap will ignite the gun cotton and cause explosive of the charge within the shell. It will be noted that when the setting key has been removed, 75 action of the slide 21 or latch will be such as to allow the firing pin 28 to move outwardly in time to allow the explosive charge to be positioned thereunder without interference and it might be stated at this time 80 that the spring 37 is sufficiently tempered to withstand the starting inertia of the shell when the same is discharged from the shell case to prevent accidental movement of the firing pin. 85

In Figure 5, from the mechanism illustrated, it would appear that the setting key 26 had been withdrawn and the movement of the cap bar 16 is limited by a suitable projection 41 carried thereby, which contacts with the guide and prevents movement of the cap bar any further than will be sufficient to position the detonating cap in alignment with the firing pin. 90

It is evident that any form of construction 95 may be embodied in order to carry out the principle of my invention and while I have made use of a rubber safety pad in the cap bar 16, it is to be understood that any suitable material might just as well be used and any suitable igniting agent may be employed for the cap 33 and any means may be incorporated in connection with the firing pin to prevent untimed movement of the firing pin, as at the instant of discharge of the 100 shell from its case. 105

It will be evident, therefore, that I have provided a safety mechanism made of few parts, which may be used during the filling, handling and transportation of shells of this 110 character and which will prevent injury to the handlers thereof due to premature explosion of the shell.

A further advantage of my invention is the provision of a safety mechanism which 115 embodied few parts, which can be easily assembled and which will prevent accidental discharge of the shell.

While I have illustrated and described my invention with some degree of particularity, I realize that in practice various alterations 120 therein may be made. I therefore reserve the right and privilege of changing the form of the details of construction or otherwise altering the arrangement of the correlated parts without departing from the spirit of the invention or the scope of the appended 125 claim.

Having thus described my invention what I claim as new and desire to secure by United States Letters Patent is:—

In a projectile containing an explosive charge, a movable firing pin, means for normally urging the pin outwardly, a transversely movable slide, a detonator on the slide, an anti-ignition pad on the slide, a spring for moving the slide to position the

detonator under the firing pin, a projection 10 on the pin, latch attached to the slide moving spring arranged to engage said projection to keep the pin in its inward position and means for releasing said slide and said pin whereby the latter will be advanced and 15 the detonator will be positioned thereunder.

In testimony whereof I affix my signature.

JOHN KOWOLCHUK. [L. s.]
